UNITED STATES PATENT OFFICE.

JAMES H. WHITE, OF NEW YORK, N. Y.

DESIGN FOR A PUZZLE-BOARD.

SPECIFICATION forming part of Design No. 31,848, dated November 14, 1899.

Application filed October 17, 1899. Serial No. 733,931. Term of patent 8½ years.

To all whom it may concern:

Be it known that I, JAMES H. WHITE, of the city of New York, borough of the Bronx, in the county and State of New York, have invented and produced a new and original Design 5 for a Puzzle-Board, of which the following is a full, clear, and exact description.

Reference is to be had to the accompanying drawing, forming a part of this specification, 10 in which the figure is a plan view of a puzzle-board, showing my design.

The design for a puzzle-board consists in its 15 leading feature of a rectangular base within which are lines forming the four sides of a main square, which is subdivided into small squares by lines running across the main square in opposite directions, and in the center is a rectangular figure, the lines forming the same being distinctive and contrasting 20 with the first-named lines, and surrounding this center figure, within the main square, are lines parallel with the sides of the center fig-

ure and connected at the ends by lines forming two half-sections and two whole sections of rectangular figures, the said lines forming 25 the figure surrounding the center figure being distinctive and contrasting with the first-named lines, and this figure is surrounded by diagonal corner-lines and lines parallel with the lines of the main square, connected by 30 inwardly-converging and meeting lines. Center lines are extended across the main square and lines extended diagonally from outlines of triangular figures. Dots are represented at the junctions of the several lines. 35

Having thus described my invention, I claim as new and desire to secure by Letters Patent—

The design for a puzzle-board as shown and described.

JAMES H. WHITE.
